UNITED STATES PATENT OFFICE.

OLIVER HALL AND VICTOR PUTNAM ROW, OF CONISTON, ONTARIO, CANADA.

MEANS FOR CONTROLLING THE DIRECTION OF CUTTING DRILL-HOLES IN ROCK.

1,380,954.

Specification of Letters Patent. Patented June 7, 1921.

Application filed June 1, 1920. Serial No. 385,703.

To all whom it may concern:

Be it known that we, OLIVER HALL and VICTOR PUTNAM Row, both residents of the town of Coniston, county of Nipissing,

5 Province of Ontario, in the Dominion of Canada, both subjects of the King of Great Britain, have invented certain new and useful Improvements in Means for Controlling the Direction of Cutting Drill-Holes in 10 Rock, described in the following specification and illustrated in the accompanying drawings; that form part of the same.

The principal objects of this invention are to eliminate the uncertainties experienced 15 in the use of the diamond drill, due to the inability to drill straight holes and thereby avoiding abortive operations and heavy and useless expense, and to devise an effective means for controlling the direction of the 20 cutting operation, thus enabling accurate borings and surveys to be made.

It is well known to those conversant with the use of diamond drills that it is practically impossible to drill a straight hole. This is due to various causes. If the drill meets a fissure plane at a narrow angle, an abnormal side thrust occurs upon the drill which deflects it in the direction of the plane of the fissure and if the hole approaches a fissure 30 at a wide angle, the tendency is for the drill to penetrate the fissure plane at right angles. The face of the bit having one side in solid formation beyond the fissure and the other side in the selvage of the fissure tends 35 to turn, the rods curving to the extent of their clearance in the hole. Other elements tending toward inaccuracy in boring are found in the condition of the boring equipment or the manner in which it is fed and 40 a curvature once started increases very rapidly.

The principal feature of this invention consists in placing a guide within the drill hole to deflect the drill in the desired direction.

45 In the accompanying drawings, Figure 1 is a sectional view of a hole showing our improved deflecting device inserted therein.

Fig. 2 is an elevational view of the drill deflector with Figs. 2^a, 2^b, 2^c, 2^d and 2^e illustrating enlarged cross sections thereof.

Fig. 3 is an enlarged detail elevational view of the drive wedge and Fig. 4 is an enlarged elevational view of the pilot wedge.

50 In carrying this invention into effect, the direction of the hole is surveyed by the use of a clinometer well known to mining en-

gineers and if it has been determined that the curvature of the hole being drilled is too great, our improved apparatus is then brought into use.

60

A dry turned wooden plug 1, grooved to allow water to pass, is pushed down into the hole with the drill rods to the point where it is desired to branch the hole. It is then allowed to swell. The drive wedge 2 is then 65 dropped into the hole and driven into the wooden plug by the use of a blank bit. The wedge 2 is formed of a cylindrical shape having a wedge point 3 at the lower end and a large recess 4 is cut in one side 70 thereof close to the base. The top surface is beveled off from above the recess 4 to the upper end, leaving a small shoulder 6 at the top against which the driving bit may operate. The cutting of the recess 4 in the 75 drive wedge makes it heavier on one side and when dropped into the drill hole the recessed side and the wedge face 5 usually face in the direction of the curvature. The position of the drive wedge may be surveyed 80 by the use of a clinometer having its lower end shaped to fit the wedge surface 5.

The pilot wedge 7 is a cylindrical metal block formed with a wedge surface 8 to coincide with the wedge surface 5 of the 85 drive wedge and at its upper end it is provided with a threaded extension 9. The pilot wedge is also provided with a central water hole 10.

The deflecting wedge 11 is a long steel bar 90 having a cylindrical surface of a diameter corresponding with that of the pilot wedge and at the lower end it is formed with a threaded hole to receive the threaded portion 9 of the pilot wedge which is screwed thereto. 95 A water hole 11' extends upwardly through the center of the wedge 11 and branches off to one side intermediate of its length. A longitudinal groove 12 is formed in the wedge 11 commencing at a point adjacent 100 to the threaded end and tapering inwardly to the top. The transverse curvature of the groove 12 is of a standard radius smaller than the radius of the wedge, for instance, an "E" radius groove is cut in an "A" radius 105 wedge.

A cross section of the metal at the upper end of the deflecting wedge, a short distance from its extremity is in the form of a thin crescent and as shown in Figs. 2^a to 110 2^d the thickness of the crescent gradually increases until it finally merges, close to the

bottom of the wedge, into the cylindrical formation.

At the top end of the deflecting wedge 11 a ring 13 is formed of the same diameter as 5 the bottom end of the wedge. This holds the wedge in place within the hole and is of assistance in placing the wedge.

In order to properly place the deflecting wedge, the deflection of the hole and the 10 relative location of the beveled face 5 of the drive wedge are determined by a careful survey. The pilot wedge 7 is then screwed on to the deflecting wedge and the relative positions of the grooved face 12 of the deflecting wedge and the beveled face 10 of the pilot wedge adjusted to insure the proper 15 location of the grooved face of the wedge 11 in relation to the hole. The pilot wedge is then secured by inserting a pin into the 20 threaded portion and both members are then placed in the hole and the pilot engages the beveled surface of the drive wedge and holds the deflecting wedge in the desired position.

25 When the wedges have thus been located a bit is lowered with a core barrel. If the drill hole is "A" size an "E" size bit is used, it passes through the hole in the collar and being guided by the metal of the wedge, 30 a hole is drilled in the face of the rock divergent from the original hole. The curved face of the deflecting wedge is "E" size, consequently the "E" bit follows the wedge without cutting into it.

35 After a preliminary drilling of a few feet, the "E" bit is removed and a special reamer bit is inserted and the collar 13 at the top of the deflecting wedge is cut away and the hole in the rock is reamed out to size "A". 40 After this has been accomplished, the regular "A" rod and "A" bit are used and an "A" hole is then continued below the wedge. The effect of this is to start a new hole branching off from the old one and the deflection of the hole is thus corrected. By 45 this method any size of drill hole may be branched without altering its size.

It has been found in practice that with the use of an apparatus such as described 50 very great accuracy in placing the wedges can be obtained and a hole of very great depth can be maintained practically straight by making careful surveys using the deflecting wedge in the manner described 55 when the deflection gets beyond certain prescribed limits.

It will be readily understood that with the use of this apparatus a single hole can be branched in any desirable direction and at 60 any desirable depth, enabling the engineers to swing a series of holes in different directions from a single initial drill-hole and to thus cover an exceptionally wide area of rock.

65 An apparatus such as described has been

found to be very beneficial and has effected very great saving wherever it has been used, it having been thoroughly tested in various formations and at very great depths and by its use the operators have been able 70 to completely control the direction of operation of the drilling machinery.

What we claim as our invention is:—

1. Means for controlling the direction of cutting drill-holes in rock, comprising, a 75 longitudinally tapered member adapted to be inserted into the drill-hole with the thin end uppermost, and means adapted to be inserted into and definitely located in the drill hole for locating and securing said tapered 80 member in a definite position in relation to the direction of the drill-hole.

2. Means for controlling the direction of cutting drill-holes in rock, comprising, a 85 plug adapted to be secured in the drill-hole, a member adapted to be secured to said plug and having a locating surface at its upper end, and a deflecting wedge having a longitudinally beveled surface and a locating surface at its lower end adapted to coincide 90 with the locating surface of the aforesaid member.

3. Means for controlling the direction of cutting drill-holes in rock, comprising, a 95 plug adapted to be secured in the hole, a drive wedge having a sharpened lower end adapted to enter the plug and a beveled upper end, said drive wedge being recessed on the side adjacent to the bevel, and a deflecting wedge having its longitudinal surface 100 beveled from the top end and having a beveled lower end adapted to coincide with the beveled upper end of the drive wedge.

4. Means for controlling the direction of cutting drill-holes in rock, comprising, a 105 plug adapted to be secured in the drill-hole, an eccentrically weighted cylindrical member having a sharpened wedge at its lower end and a beveled upper end, a deflecting wedge beveled longitudinally at one side, 110 and a pilot wedge rotatably adjustable on said deflecting wedge and having a beveled lower end adapted to coincide with the beveled end of the beveled cylindrical member.

5. Means for controlling the direction of 115 cutting drill-holes in rock, comprising, means for plugging the drill hole having a locating upper surface, and a deflecting wedge having a ring at the top end and a longitudinal concaved groove extending 120 downwardly from said ring and tapering off toward the bottom, the lower end of said deflecting wedge having a locating surface adapted to engage the locating surface of the plugging means.

6. Means for controlling the direction of cutting drill-holes in rock, comprising, means for plugging the drill-hole presenting a locating surface at the upper end, a deflecting wedge formed of a cylindrical mem- 130

ber to fit within the drill-hole having a locating surface at the lower end and formed with a transversely arc-shaped concavity on one side tapering from the bottom and upwardly to a thin edge at the top and forming a guide for the drill.

7. Means for controlling the direction of cutting drill-holes in rock, comprising, a turned wooden block having surface grooves 10 for the passage of water adapted to be inserted into the drill-hole, a drive wedge having a pointed lower end adapted to enter

said plug and formed with a recess in one side thereof and a beveled upper surface and a driving shoulder at the upper end of said 15 bevel, a pilot wedge beveled to correspond with the beveled surface of the drive wedge, and a deflecting wedge adjustably secured to said pilot wedge and having its longitudinal surface formed with a transversely 20 concaved taper extending to the upper end.

OLIVER HALL.
VICTOR PUTNAM ROW.
